Primary Examiner — Elizabeth A. Albert(74) *Attorney, Agent, or Firm* — Lando & Anastasi, LLP(57) **CLAIM**

The ornamental design for a pad holder, as shown and described.

DESCRIPTION

FIG. 1 is a perspective view of the pad holder;

FIG. 2 is a front view of the pad holder;

FIG. 3 is a rear view of the pad holder;

FIG. 4 is a left side view of the pad holder;

FIG. 5 is a right side view of the pad holder;

FIG. 6 is a top view of the pad holder;

FIG. 7 is a bottom view of the pad holder;

FIG. 8 is a perspective view of the pad holder illustrating a separation between a first portion and a second portion; and,

FIG. 9 is a perspective view of the pad holder illustrating a separation between a first portion and a second portion.

The broken lines shown in the drawings illustrate portions of the pad holder and form no part of the claimed design.

1 Claim, 8 Drawing Sheets(56)
